UNITED STATES PATENT OFFICE.

GEORGE E. MADISON, OF FLINT, MICHIGAN, ASSIGNOR TO GENERAL MOTORS CORPORATION, OF DETROIT, MICHIGAN, A CORPORATION OF DELAWARE.

FOLDING TOP FOR AUTOMOBILES.

1,396,862.

Specification of Letters Patent.

Patented Nov. 15, 1921.

Application filed January 2, 1920. Serial No. 348,757.

To all whom it may concern:

Be it known that I, GEORGE E. MADISON, a citizen of the United States, and a resident of Flint, county of Genesee, and State of Michigan, have invented certain new and useful Improvements in Folding Tops for Automobiles, of which the following is a full, clear, concise, and exact description, such as will enable others skilled in the art 10 to which the invention relates to make and use the same, reference being made therein to the accompanying drawings, which form a part of this specification.

My invention relates to tops for vehicles; 15 and particularly to folding tops designed for use with motor propelled vehicles and having a plurality of pivotally supported bows and a fabric covering secured thereto and which when in their extended position support the top up and over the body of the vehicle, but which bows may be collapsed and folded and made to assume a position at the rear of the vehicle body when the protection afforded by the top is not necessary 20 or desired.

The principal object of my invention is to provide a top which when up and in use will present the general appearance of the type of top commonly referred to as the California top, but which at the same time is foldable which is not ordinarily the case with the type of top in question.

A further object of my invention is to provide a folding top having the usual fabric cover secured in place upon the horizontal top portions of the bows thereof, and the usual back curtain; together with side quarter portions which extend downward from said fabric cover and are provided with depending 35 flaps adjacent their rear ends which may be detachably secured relative to the back curtain, preferably to the forwardly extending sides or wings thereof, when the top is up and in use, but which flaps may be unfastened from the back curtain and folded along and in with the fabric covering and bows when the top is to be taken down and folded at the rear of the vehicle body.

A further object of my invention is to provide an improved top wherein the sides of 50 the bows thereof and the pivotal connections between the various bows are hidden by the side quarter portions thereof and the for-

wardly extending wings of the back curtain, and which top as a whole may be readily 55 folded, which has not heretofore commonly been the case in tops having partially closed sides or in the semi-inclosed type of top; the folding being made possible by the unfastening of a single joint or seam in the top structure upon each side thereof and at the rear 60 end of the side quarter portions of the top.

Further objects of my invention will appear from the following description of my invention, and from the concluding claims 65 wherein the particular and distinguishing features thereof are enumerated.

My invention is illustrated in its preferred form in the drawing accompanying and forming a part of this specification; although it will be appreciated that the drawing is for illustrative purposes only, and for the purpose of enabling the following description of my invention to be better followed and understood; and that such variations and modifications of my invention as come within the scope of the concluding claims 70 are equally within the scope thereof, and are intended to be covered by the patent to be secured therefor.

In the drawing:

Figure 1 is a view showing one form of my improved folding top in side elevation, the automobile body to which the top is applied being shown conventionally, and in 75 outline only.

Fig. 2 is a similar view showing the top before the near side quarter portion thereof is put in place.

Fig. 3 is a view showing the near side 80 quarter portion by itself.

Figs. 4 and 5 are views similar to Fig. 1, but showing my invention as applied to different particular types of tops.

Referring to the drawing, the reference 95 numeral 5 designates a motor vehicle body in outline and in a conventional manner, as it will be appreciated that my invention is in no way limited to use with any particular kind or style of vehicle body; and the reference numeral 6 designates a main supporting bow located adjacent the rear end of the body and which serves as a support for the entire top structure. This bow is of the usual U-shaped form having a substantially 100 horizontal top portion, and the lower ends 105

of the sides thereof are pivotally connected with the sides of the vehicle body at two points 7 one upon each side of the body and opposite one another.

5 The rearmost or main supporting bow 6 is substantially the same in each of the several forms of my invention illustrated, and in each case the said main bow serves as a support for a plurality of supplemental bows located in front thereof and over the upper horizontal portions of which the fabric covering 8 of the top is stretched. Thus in the form of my invention illustrated in Figs. 1 and 2 two supplemental bows 9 and 10 are supported from the main bow 6, the former being pivotally connected directly to the main bow at oppositely located points 11 while the latter is supported from the main bow through pairs of links 12 disposed one 15 pair upon each side of the top. In the form shown in Fig. 4 three supplemental bows 13, 14 and 15 are disposed in front of the main rear bow; while in the form shown in Fig. 5 four auxiliary bows 16, 17, 18 and 19 are 20 supported in front of the rear bow. In all cases the supplemental bows provide a collapsible frame work or support for the fabric cover of the top, and in each case both the supplemental and main bows together with 25 the fabric covering which they carry may be folded and made to lie compactly at the rear end of the vehicle body, as is usual in foldable tops of the general class to which my invention relates. In passing, it may be here 30 stated that the particular form, number, method of support from the main bow, and other features of the collapsible frame work provided by the supplemental bows are in no way involved in this present invention, 35 and may be varied to suit the designer of the top in each particular case. In tops of the general class to which my invention relates the forward one of the supplemental bows and thus the forward end of the top is 40 commonly detachably secured to the upper ends of oppositely disposed upright standards 20, to thereby hold the front of the top in proper 45 position relative to the body and prevent lateral movement of the said front portion, 50 which standards commonly support a windshield between them but which is not shown in the drawing, being unimportant in this present case.

The reference numeral 21 designates the 55 back curtain of the top the upper end or edge of which is secured to the horizontally extending portion of the rearmost bow 6 along a line the position of which is indicated by the reference numeral 22, and the 60 forwardly extending side portions or wings 23 of which are commonly secured along their upper inclined edges 24 to the said rearmost bow; there being one such side or wing upon each side of the vehicle in the embodiment of my invention illustrated. The

lower end of the back curtain is secured along its entire length to the vehicle body as will be understood.

Depending from the sides of the top cover 8 and disposed one upon each side of the top structure are the side quarter portions 25 the near one only of which is shown in Figs. 1 and 3, while the far one appears in Fig. 2. The upper edges 26 of these side quarter portions are permanently secured to the top 75 cover 8 along a suitable seam, while the rear edges of said portions lie adjacent the rearmost main supporting bow of the top. The upper portion 27 of this rear edge is permanently secured along its length to the rearmost bow 6 as by a series of nails, while the lower portion 28 of said rear free edge is detachably secured relative to said bow and relative to the side wings of the back curtain; preferably by means of a series of co-operating pairs of separable fastening members indicated at 29, one member of each pair being carried by a side quarter and the other by the wing of the back curtain adjacent which it lies in the embodiment of my invention illustrated, although as a matter of course any suitable kind of fastening means or separable fastening members may be used.

The shape of the side quarter portions is commonly made such that a triangular flap 95 portion 30 is provided adjacent the rear end of each and which flap depends from the lower edges thereof, in which case the part of the rear edge of a side quarter which is fixedly secured relative to the rearmost bow 100 and the adjacent side wing of the back curtain corresponds with the rear edge of the triangular flap as will be understood.

In the form of my invention illustrated in Fig. 4 the triangular flap portions 31 extend downward from the side quarters 32 farther than in Figs. 1 to 3, and the apices of said portions lie substantially at the upper edge of the vehicle body; while in the form illustrated in Fig. 5 the flap 33 is 110 substantially the same as in Figs. 1 to 3, although the top has a total of five bows instead of three as in the form of my invention first herein described.

In view of the premises it will be appreciated that when the top is up and the rear inclined edges 28 of the side quarters illustrated in Figs. 1 to 3, or the corresponding edges of the equivalent side quarters in the forms illustrated in Figs. 4 and 5, are 115 fixedly secured in place by means of the fastening members as above explained, the top as a whole will present the appearance of the California type of semi-enclosed top; and the side portions of the various bows, 120 and in fact all the elements of the top involved in the support of the fabric covering thereof in an extended or up position will be hidden by the side quarters and by the side wings of the back curtain. When, how- 130

- ever, the detachable fastening members referred to are unfastened or the rear free edge of the flap portions otherwise disengaged from the element or portion of the 5 top to which they are detachably secured the top as a whole may be readily folded and made to assume a collapsed condition at the rear end of the vehicle body, the flap portions of the side quarters being folded 10 inward along portions indicated approximately by the dotted lines 34, and caught in the creases or folds of the fabric cover, the side quarters, and the back curtain during the folding operation, as will be understood.
- 15 Having thus described and explained my invention, I claim and desire to secure by Letters Patent:
1. In a motor vehicle top and in combination with a plurality of supporting bows, 20 and a back curtain secured along its upper edge to the rearmost of said bows; a fabric cover supported by said bows; a side quarter portion permanently secured along its upper edge to the fabric cover of the top and 25 having a flap located adjacent its rear end and depending below its lower edge; and means for detachably securing said flap portion relative to the rearmost of said bows and relative to said back curtain.
- 30 2. In a motor vehicle top and in combination with a plurality of supporting bows, and a back curtain secured along its upper edge to the rearmost of said bows; a fabric cover supported by said bows; a side quarter portion permanently secured along its 35 upper edge to the fabric cover of the top and along the upper portion of its rear edge to the rearmost of said supporting bows, and having a flap located adjacent its rear 40 end and depending below its lower edge; and separable fastening members whereby said flap may be secured along one of its edges relative to said back curtain.
3. In a motor vehicle top and in combination with a plurality of supporting bows, 45 and a back curtain secured along its upper edge to the rearmost of said bows; a fabric cover supported by said bows; a side quarter portion permanently secured along its 50 upper edge to the fabric cover of the top and having a flap triangular in form and located adjacent its rear end and depending below its lower edge; and separable fastening members whereby said flap may be secured along one of its edges relative to said back curtain.
- 55 4. In a motor vehicle top and in combination with a plurality of supporting bows, a fabric cover supported by said bows, and a 60 back curtain secured along its upper edge to the rearmost of said bows and having forwardly extending sides or wings; a side quarter portion permanently secured along its upper edge to the fabric cover of the top 65 and along its rear edge to the rearmost of said supporting bows, and which side quarter is provided with a flap located adjacent its rear end and depending below its lower edge; and means for detachably securing a free edge of said depending flap to a side or wing portion of said back curtain.
- 70 5. In a motor vehicle top and in combination with a plurality of supporting bows, a fabric cover supported by said bows, and a back curtain secured along its upper edge to the rearmost of said bows and having forwardly extending sides or wings; a side quarter portion permanently secured along its upper edge to the fabric cover of the top 75 and along its rear edge to the rearmost of said supporting bows, and which side quarter is provided with a triangular flap located adjacent the rear of said side quarter and depending therefrom; and separable fastening means for detachably securing the rear free edge of said depending flap relative to a side portion of said back curtain and relative to the rearmost of said bows.
- 80 6. In a motor vehicle top and in combination with a plurality of supporting bows, a fabric cover supported by said bows, and a back curtain secured along its upper edge to the rearmost of said bows and having forwardly extending side portions or wings the 85 upper edges of which are also secured to the rearmost of said bows; a side quarter portion permanently secured along its upper edge to the fabric cover of the top and the rear edge of which side quarter lies adjacent the rearmost of the bows aforesaid; the upper portion of the rear edge of said side quarter being permanently secured to the rearmost of said bows and the lowermost portion of said free edge being detachably secured relative to the rearmost of said bows 90 and relative to a side portion of said back curtain.
- 95 7. In a motor vehicle top and in combination with a plurality of supporting bows, and a back curtain secured along its upper and side edges to the rearmost of said bows; a fabric cover supported by said bows; a side quarter portion permanently secured along its upper edge to the fabric cover of the top 100 and the rear edge of which terminates adjacent the rearmost of said bows, and the upper portion of which rear edge is permanently secured to said rearmost bow; and means for detachably securing the lower portion of said free edge relative to the rearmost of said bows and relative to said back curtain.
- 105 8. In a motor vehicle top and in combination with a plurality of supporting bows, and a back curtain secured along its upper and side edges to the rearmost of said bows; a fabric cover supported by said bows; a side quarter portion permanently secured along its upper edge to the fabric cover of the top 110 and having a flap located adjacent its rear 120 edge to the rearmost of said bows.

edge and depending below its lower edge; and means for detachably securing the rear edge of said flap portion relative to a side edge of said back curtain.

5. 9. In a motor vehicle top and in combination with a plurality of supporting bows, a fabric cover supported by said bows, and a back curtain secured along its upper edge to the rearmost of said bows and having forwardly extending sides or wings the free edges of which are also secured to said rearmost bow; a side quarter portion permanently secured along its upper edge to the fabric cover of the top and the rear edge of which lies adjacent the rearmost of said bows and is fixedly secured thereto throughout its upper portion; and means for detachably securing the lower portion of said free edge to a side or wing portion of said back curtain.

10. In a motor vehicle top and in combination with a plurality of supporting bows, and a back curtain secured along its upper edge to the rearmost of said bows; a fabric cover supported by said bows; a side quarter portion permanently secured along its upper edge to the fabric cover of the top and the rear edge of which lies adjacent said rearmost bow and said back curtain; and means for detachably securing the rear edge of said side quarter portion relative to said rearmost bow and relative to said back curtain.

11. In a motor vehicle top and in combination with a plurality of supporting bows, a fabric cover supported by said bows, and a back curtain having forwardly extending sides or wings; side quarter portions unitarily connected with said fabric cover and depending therefrom, and which side quarter portions are provided with flaps adjacent their rear ends and depending from their lower edges; and means for detachably

securing the rear free edges of said flaps and the forward edges of said wing portions together.

45

12. In a motor vehicle top and in combination with a plurality of supporting bows, a fabric cover supported by said bows, and a back curtain having forwardly extending sides or wings secured along their free edges to the rearmost of said bows; side quarter portions unitarily connected with said cover and depending therefrom, and which portions are provided each with a triangular flap located adjacent its rear end and depending therefrom; and separable fastening means for detachably securing the rear free edges of said depending flap portions relative to the forward free edges of the wings of said back curtain, and relative to the rearmost of said bows.

50

13. In a motor vehicle top and in combination with a plurality of supporting bows, a fabric cover supported by said bows, and a back curtain having forwardly extending sides or wings the free edges of which are secured to said rearmost bow; said fabric cover having side quarter portions connected therewith to form a unitary structure and depending therefrom, and which fabric cover, side quarters and back curtain are secured along the upper edge and part way down the sides of the rearmost of said supporting bows; said side quarters having triangular flaps located adjacent the rear ends thereof and depending therefrom, and the rear free edges of which flaps overlie portions of the sides of the rearmost of said supporting bows; and separable fastening members whereby the rear free edges of said depending flaps may be secured relative to said rearmost supporting bow.

65

In testimony whereof I affix my signature.
GEORGE E. MADISON.
